WIRE FEED FOR MAGNETIC RECORDERS

Irving A. Stone, Detroit, Mich., assignor to Wire-
order Corporation, Detroit, Mich., a corpora-
tion of Michigan

Application July 3, 1946, Serial No. 681,213

4 Claims. (Cl. 274—11)

1

The present invention relates to magnetic wire sound recording and reproducing apparatus.

In apparatus for this purpose, it is customary to feed the wire from a wire spool to a take-up spool during recording or play back and thereafter rewind the wire on the wire spool. In the past it has been the practice to employ a small wire spool for convenience in manufacture and to facilitate storage of recordings, and a large diameter take-up spool which is driven at constant speed. With this arrangement the take-up spool must be much larger in diameter than the wire spool; otherwise the speed of the wire will vary to an objectionable extent as the thickness of the wire layer on the spool builds up. Due to the difficulty of handling the individual spools of very fine wire and of threading the wire by hand into the recording head, it has been proposed that both spools be enclosed in a removable magazine so that no handling of the separate spools or of the wire is required. This necessitates the use of a small take-up spool in order to reduce the size and cost of the magazine, and the small take-up spool, in turn, requires the use of special means to insure a constant wire speed. The co-pending application of Mortimer A. Neff, Serial No. 608,531, filed August 3, 1945, is directed to a machine adapted for use with a magazine, and the present invention constitutes an improvement over the machine of that application, although a number of the features of the present invention may be employed to advantage without a magazine.

It is the general object of the invention to provide a magnetic wire sound recording and reproducing apparatus of novel and improved design construction and mode of operation.

Another object of the present invention is to provide an improved wire feeding means of the type which grips the wire at a point between the spools and which includes means for exerting considerable pressure on the wire without requiring exertion of any appreciable manual effort to either grip or release the wire.

Another object of the present invention is to provide improved manually or automatically operable means for stopping the apparatus.

Still further, the present invention contemplates means to lock the control mechanism in either of two operating positions and further means responsive to a predetermined unwinding of the wire on the spools of either spindle for releasing this locking means and thereby stopping the machine.

Further objects and advantages of the present

5

invention will be apparent from the description which follows when considered in connection with the accompanying drawings, in which like numerals indicate like parts wherever shown, and wherein:

Figure 1 is a plan view of the chassis with a wire spool and a take-up spool in assembled relation and with the top casing removed, illustrating certain of the apparatus internally of said chassis;

Figure 2 is a plan view of the upper portion of the apparatus with the casing broken away and illustrating the driving mechanism of the present invention;

Figure 3 is an elevational view taken on line 3—3 of Figure 2, illustrating the mechanism of the machine of the present invention, with the parts in the play position;

Figure 4 is an elevational view similar to Figure 3 and illustrating the mechanism of the machine of the present invention in an intermediate position prior to being brought into play position;

Figure 5 is an elevational view similar to Figure 3 and illustrating the various parts thereof in position to rewind the wire;

Figure 6 is an elevational view taken in the direction of arrow 6 on Figure 2 and illustrating the means for driving the level-winding mechanism on the left-hand side of the apparatus;

Figure 7 is a sectional elevation taken on line 7—7 of Figure 2 with certain of the parts broken away;

Figure 8 is a sectional elevation taken on line 8—8 of Figure 1 and illustrating the release plate;

Figure 9 is a sectional elevation taken on line 9—9 of Figure 1 showing the cam operated switch for the motor;

Figure 10 is a sectional elevation taken on line 10—10 of Figure 1 illustrating the brake for the take-up spool;

Figure 11 is a section taken on line 11—11 of Figure 1 showing the control rod;

Figure 12 is a section taken on the line 12—12 of Figure 6 to illustrate the construction of one of the eddy current clutches;

Figure 13 is a partially sectioned elevational view of one of the spools, with the wire substantially unwound therefrom to illustrate the automatic stop operation;

Figure 14 is a section taken on line 14—14 of Figure 5; and

Figure 15 is a section on line 15—15 of Figure 1 showing the pad for supporting the feed roll yoke positioned against the cam arm.

2

The apparatus of the present invention in-

cludes a base 1, in the form of a casting, which is enclosed within a housing or cover 2, which cover is only partly shown in Figure 2, being broken away in order that the mechanism of the present apparatus might be more clearly seen.

This base portion 1, as well as the housing 2, may be made of any suitable construction and it will be understood that the electrical circuits and elements of the magnetic apparatus may be enclosed within the same housing, if desired. Since these electrical circuits form no part of the present invention, they are neither illustrated nor described herein, but it will be understood that they are of any desired or conventional construction.

A wire spool 3 and a take-up spool 4 may be mounted upon spindles 5 and 6, respectively, and if a magazine is to be used for such spools, cover 2 is designed to receive the same in any desired manner, such as that shown in the aforementioned Neff application.

To drive wire spool 3 and take-up spool 4, a constant speed electric motor 7 is mounted by means of suitable supports provided therefor in the base 1. Means are provided for selectively driving either or both of the spindles 5 and 6 for said wire spool and take-up spool respectively, from said motor 7 through magnetic clutches of the eddy current type, which will permit continuous slipping in the drive connection between the spindles and the motor. Thus, as best shown in Figures 2 and 6, the spindle 6 is journaled for rotation in bearings 8, 9 and 10 carried by a pillow block 11 which is pivotally secured to the base 1 by a vertical pivot pin 12, positioned near the forward face of the housing 2 and secured in place by means of nut 13 and lock nut 13a. The rearward end of spindle 6 carries a cuplike member 14, which is of nonmagnetic metal but which is a good conductor of electricity and, as shown in Figure 12, surrounds the multipole magnet rotor 15 and fits within an iron or soft steel housing 16. The housing 16 and the permanent, multipole magnet 15 are fixed to a sleeve or bushing 17. This bushing 17 is rotatably supported by spindle 6 and provides for independent rotation of housing 16 and magnet 15 about such shaft. The elements 14, 15 and 16 constitute an eddy current clutch, with the result that, on rotation of the housing 16, a rotary torque will be transmitted to the cup 14 and, consequently, to the spindle 6 for driving the take-up spool 4. The shaft of motor 7 is provided at the rear with a drive roller 18 having a circumferential rubber rim 19 adapted to frictionally engage and rotate the housing 16, and, as stated in the foregoing, causes a rotary torque to be transmitted to the cup 14 and thus drives the spindle 6 and take-up spool 4.

In a similar manner, spindle 5 is supported upon a pivoted pillow block 20 which is identical in construction and mode of operation to the previously described pillow block 11, and this spindle 5 is likewise connected to the drive roller 18 by means of the housing of a magnetic, eddy-current clutch 21, identical to the previously described magnetic clutch 14-16. The rearward end of pillow blocks 11 and 20 is held by means of contractible springs 22 and 23, respectively, in such position as to normally hold the housings of magnetic clutch 14-16 and magnetic clutch 21 in engagement with the member 19 on roller 18 at the same time, with the result that spindles 6 and 5 are subject to a winding torque in a counterclockwise direction when motor 7 is running

and the remaining parts are in the stop position. As will hereinafter become more clear, the wire is so wound on wire spool 3 and take-up spool 4 that the winding torque thus applied to spindles 5 and 6 tends to wind the wire on both spools simultaneously and, consequently, substantially balance each other. As a result, when the parts are in the stop position and the motor is started, the slack wire between the spools is taken up with substantially no movement of either spool.

As a means for selectively controlling the operation of the apparatus of the present invention, a rotatable control knob 24 is provided. Such knob 24 is fixed to control shaft 25 which is journaled at its forward end within bearing 26, of the support 27 provided on the forward wall of casting 1, and has the opposite end in bearing 28 in base 1, as may be seen in Figure 1. This control knob may be rotated through substantially 180° and provides for selectively placing the apparatus of the present invention in operation or stopping the same. Connected to the control knob is a main cam, indicated generally at 29, and having cam surfaces 30, 31 and 32. When the control knob 24 is in its stop or off position, the main control cam will be in such position that the cam surface 30 depresses a button 33 of switch 34 which controls the supply of current to motor 7. When the button is depressed, the switch is opened. At the same time, the surface of cam 31 is free from a pad 35 on the bell crank shaped lever 36, shown best in Fig. 10, which is pivoted at 37 to base 1, permitting the brake surface 38 on such lever 36 to be forcibly held by means of spring 39 against the outer diameter of cup 14. It will be apparent that upon initially moving control knob 24 in either direction from the stop position, cam 30 will disengage the button 33, while cam 31 will enter into engagement with pad 35 of lever 36. When this occurs, switch 34 closes the motor circuit, thereby starting the motor and releasing cup 14.

As shown in Figure 1, a rod 40 is threaded into the web portion of pillow block 11 and positioned in such manner that the rounded end thereof may contact cam 32, in which position rod 40 is locked by means of a lock nut 41 abutting the web of the pillow block. This rod 40 is adapted to be shifted within the slotted openings provided at 42 and 43 in the base 1. In like manner, a rod 44 is threaded into the web of pillow block 20 and locked in position by means of lock nut 45 in such a manner that its rounded end may enter into engagement with cam 32. Rod 44 is also slidably mounted within slotted openings 46 and 47 provided in base 1. When control knob 24 is in the stop or off position, cam 32 does not contact the rounded ends of either rod 40 or rod 44, and the member 19 of driving wheel 18 on motor 7 may contact the housings of both magnetic clutches for driving the same and causing the slack in the wire to be taken up, as previously described. However, after initial rotation of control knob 24 to start motor 7 and release brake 36, continued rotation of control knob 24 in either direction will cause cam 32 to come into contact with the rounded end of rod 40 or 44, depending upon the direction of rotation of such control knob, and thereby effect pivotal shifting of one of the pillow blocks. This causes disengagement of one or the other of the housings from the frictional drive roller 18. Cam 32 is so positioned upon main control cam 29 that when control knob 24 is rotated counterclockwise from a stop or off position to rewind position, the final portion of

the movement of shaft 25 will result in engagement of cam 32 with the rounded end of rod 40 serving to move pillow block 11 pivotally about pin 12, thereby disengaging the housing 16 from the motor driving wheel 18. Similarly, rotation of control knob 24 in a clockwise direction toward play or record position, effects engagement of cam 32 with the rounded end of rod 44 causing pillow block 20 to shift pivotally for moving magnetic clutch 21 out of engagement with the driving means. However, in this case clutch 21 is disengaged in advance of completion of the movement of the knob to play or record position.

The means for engaging and driving the wire when it is being wound upon the take-up spool 4 is shown in Figures 3, 4 and 5. This means comprises a roller 48 mounted on the forward end of the motor shaft and adapted to be brought into engagement with a capstan drive roller 49. This roller 49 is rotatably supported by a shaft 50 journaled for rotation in the bearings 51 and 52 of a yoke 53 which is pivotally mounted by means of a pin 54 on an upwardly projecting lug 55 provided on base 1. The shaft 50 projects forwardly through the bearings provided on yoke 53, as best shown in Figure 2, and carries a nonferrous metallic capstan wire drive roller 56.

The capstan drive roller 49 is only in engagement with roller 48, on the forward end of motor 1, when the control knob is rotated to play position, and this engagement is brought about at the end of the rotation of the control knob in such direction. In order to effect such engagement, a lever 57 is secured to the lower end of yoke 53 and extends laterally substantially normal to such yoke. Yoke 53 is urged by a spring 51a in a direction to force a pad 58 on the outer end of lever 57 into engagement with an annular portion of a sleeve 59. Sleeve 59 is also mounted upon control shaft 25 for rotation therewith by means of control knob 24. As may be seen in Figure 15, the sleeve 59 is provided at one point with a flat, and when control knob 24 is turned to play position, pad 58 is urged into contact with the flat, thereby allowing capstan drive roller 49 to contact roller 48 and effecting driving of the capstan drive roller and capstan roller 56.

In order to effect a driving engagement between the wire and the capstan roller 56 in play position, there is provided a rubber pinch roller 60 carried by pinch roller arm 61 also pivotally supported by pin 54. As will hereinafter become more clear, the wire is pinched between rollers 56 and 60 with considerable pressure to establish a driving connection between the wire and roller 56. When the control knob is in off position or in the rewind position, which latter position is illustrated in Figure 5, the roller 60 is out of engagement with roller 56. The arrangement is such that rotation of control knob 24 toward play position first effects starting of motor 1 to start rotation of spindles 5 and 6 and thereby initially tensioning the wire. In order that motor 1 may come up to speed as rapidly as possible, continued rotation of the control knob in this direction next effects disengagement of magnetic clutch 21 by shifting pillow block 20 outwardly. This relieves motor 1 of the torque load imposed by such clutch. When clutch 21 is disengaged from drive roller 19, its housing engages brake 62, which is carried by a stationary bracket 63. Thereafter, on continued movement of the knob, the pinch roller is swung into engagement with the capstan roller 56. Subsequent to such engagement, means operated by further movement

of knob 24 applies a pinching pressure to the pinch roll. By the time all of these functions have been performed the motor is up to speed and substantial torque is being applied to the 5 take-up spool. The capstan drive roller is then engaged with roller 48 by the final movement of knob 24. The mechanism for operating the pinch roller includes a pair of arms 65 and 66 fixed to the previously mentioned sleeve 59, which is 10 pinned at 64 to shaft 25. The arms 65 and 66 rotatably support a roller 67 which, on rotation of sleeve 59, contacts the lower curved edge 69 on pinch roller arm 61, serving to rotate such arm about pivot pin 54 in a counterclockwise and upward direction. This elevates roller 60 and therefore the wire 70 until, when the parts are in the position of Figure 4, the wire is engaged between rollers 56 and 60.

Thereafter, continued rotation in this direction operates the pressure applying means which 20 forces roller 60 against roller 56 with a heavy pressure. This means includes an arm 72 having a slot 71 formed at one end. The arm 72 is pivotally mounted by means of a slot 73 in its 25 upper end which fits over a pin 74 on an ear 75 that projects rearwardly from the yoke 53. To retain arm 72 on pin 74, a relatively stiff spring 76, which may be seen best in Figure 14, has one end thereof secured to pin 74 and the other 30 end fixed to a clip 77 which is pinned to arm 72 by means of a roller 78, permitting the force exerted by said spring to maintain arm 72 in position on pin 74.

It will be observed that a portion of arm 72 35 lies against a projecting portion 61a of pinch roller arm 61, and that roller 78 is adapted to engage the curved edge 79 of this portion 61a.

When the parts are in the off or rewind position, the roller 78 engages the left-hand extremity of edge 79, as shown in Fig. 5, in such a manner that the line of the force exerted on edge 79 by roller 78 passes slightly to the left of the center line of pin 54. Consequently, spring 76 45 exerts no force tending to elevate arm 61 and may exert a slight force tending to hold it down. As clearly shown in the drawings (Figs. 4 and 5), the upward movement of arm 61, previously described, causes roller 78 to move along a portion of edge 79 which is arcuate in form and concentric with pin 74. Accordingly, no change in 50 the length of spring 76 occurs during such movement. As a result, spring 76 offers no resistance to rotation of knob 24.

Continued rotation of the control knob after 55 the parts reach the position of Figure 4, causes roller 68 to enter slot 71 and move arm 72 in a counterclockwise direction about pin 74, thus continuing the movement of roller 78 outwardly along the remainder of the edge 79 on roller arm 61. This remaining portion of edge 79 is concentric with pivot pin 74 when rollers 56 and 60 are engaged. Consequently, the length of spring 76 60 remains constant during the swinging movement of arm 72 as roller 78 travels along the curved edge 79. This increases the lever arm of the spring force acting on arm 61 and thereby increases the pinching force on wire 70. Inasmuch as the length of the spring 76 remains unchanged throughout this operation, it will be appreciated 65 that at no time does the spring resist turning of the control knob 24.

During this rotation of control knob 24 and 70 slightly after pin 68 enters slot 71 in arm 72, but in advance of the time roller 78 reaches the outermost end of the curved edge 79, roller 67, which

was in engagement with the lower curved edge 69 on the pinch roller arm 61, moves into engagement with the curved lower edge 80 of an arm 81. This arm 81 is also pivotally mounted on pin 54 and rotatably supports at its outer end a glass roller 82. Normally, roller 82 is in a lowered position, as illustrated in Figure 5, due to the effect of the spring 83 which is secured to a lug 84 on arm 81 and to pin 85 positioned in base 1. However, roller 67, now in engagement with edge 80 of arm 81, causes such arm to move upwardly and counterclockwise, allowing roller 82 to bring wire 70 into a playing and recording head 86.

When the control knob reaches the limit of this clockwise rotation, it is automatically locked in that position by means of a latching mechanism. This mechanism comprises a latch plate 87 which is mounted by means of pins 88 and 89 on pivoted supported levers 90 and 91, respectively, at opposite extremities of such plate. The plate is normally in latched position and against a stop 92 at the left end thereof by means of a spring 93 fixed between the left end of the plate and base 1.

Within an opening 94 in the latch plate 87 there is provided a downwardly directed latching finger 95 having a retaining slot 96. Toward the end of the clockwise rotation of the control knob, the lower surface of latch 95 is engaged by pin 97 carried in one extremity of the irregularly shaped arm 98 which is an integral part of the previously mentioned sleeve 59. This engagement causes the latch plate to move toward the right and spring 93 to expand. As soon as pin 97 clears the upper edge of the latch finger 95 which, as stated in the foregoing, occurs when the control knob reaches the limit of clockwise rotation, spring 93 contracts, returning the latch plate 87 toward the left, and locking pin 97 in slot 96, as illustrated in Figure 3.

Assuming the mechanism is locked in play position, the same may be manually unlocked for returning the control knob to off position at any instant regardless of whether or not the wire is completely unwound from wire spool 3. Means, to be later described, are provided for automatically unlocking and stopping the mechanism before all wire is completely unwound from either spool; however, at this point only the manual stop is described.

This stop comprises a stop button 99 positioned to move slidably in an opening provided therefor in base 1 immediately below control knob 24. Stop button 99 is connected to a bell crank 100 which, in turn, is pivotally secured at 101 to the bottom of post 102. This post 102 depends from the previously described bracket 21 and is of such length that the free end 103 of the bell crank may contact an inwardly directed tab 104 on latch plate 87. When stop button 99 is pressed inwardly, the free end 103 of the bell crank forcibly bears against tab 104, causing latch plate 87 to move toward the right sufficiently to free pin 97 from slot 96. At that time, a spring 105 returns the control knob 24 to off position.

This spring 105 extends between lug 106 on arm 98 and base 1 and is normally horizontal with respect to base 1, tending to retain control knob 24 in off position or return it to that position. However, rotation of the control knob to play position causes this spring to elongate and, therefore, as soon as pin 97 is freed from slot 96 in latch 95, spring 105 returns control knob 24 to off position. When this occurs, of course, pinch roller 60 and glass roller 82 are lowered,

releasing and lowering wire 70, both eddy current clutches are engaged with the drive roller 18, the motor switch is opened and all operation of the mechanism ceases.

Thereafter, if it is desired to rewind the wire, control knob 24 is rotated counterclockwise. This starts motor 7 again and releases brake 36, allowing the magnetic clutches to initially tension the wire between the spools. Further rotation of the control knob permits cam 32 to contact rod 40 for shifting pillow block 11 to disengage clutch 14-16 from motor roller 18 and bringing the same into contact with an adjacent brake 107 on bracket 107a. Brake 107 is made of felt and is designed to slow take-up spool 4 only sufficiently to prevent overrunning and throwing of a loop during rewind. In this operation, clutch 21 is substantially unopposed and, consequently, a rapid rewind results.

At the same time, this counterclockwise rotation of the control knob moves pin 97, on arm 98, into engagement with a latch finger 108 on latch plate 87. Such latch finger is spaced from latch finger 95 and is so disposed as to extend into opening 94 and be contacted by pin 97 as the same is rotated in this direction. Continued rotation of the control knob in this manner serves to effect shifting of latch plate 87 toward the right until pin 97 clears latch finger 108. When this occurs, pin 97 is locked in retaining slot 109 by the action of spring 93 as the same returns latch plate toward the left.

After the rewinding operation is complete, the control knob is simply returned to off position by releasing the latch plate and all portions of the mechanism return to the off position.

Because of the relatively great speed of rotation of the take-up spool in this rewind operation, it is particularly desirable that a retarding force be applied to the drive connection at the spool side of the yielding clutch mechanism 14-16 when the control knob is returned to off position. As the control knob returns to off position, clutch 14-16 re-engages motor roller 18 and this imposes a counter rotative torque tending to stop rotation of spool 4, but such retarding is effective at the driving side of the clutch. Due to the slippage between clutch elements 14-16, there is a tendency, because of the speed of rotation of spool 4, to continue rotating. For this reason, additional braking is provided on the spool side of such clutch. The previously described brake 36 supplies this additional braking as it engages cup 14 and thus prevents throwing of a loop in the wire when the control knob is returned to off position by spring 105.

In order to insure that the playing or recording head 86 will make proper engagement with wire 70 during recording or the reproducing of sound without interfering with the necessary level winding of the wire on the take-up spool 4 and to avoid the use of a separate level winding mechanism, the playing or recording head, in accordance with the present invention, is itself mounted upon a level winding mechanism in the manner illustrated in Figures 2, 3, 4 and 5. As there shown, the pick-up head 86, which is of conventional construction, is fixed to a bar or a rod 110 which is inserted in an opening provided therefor in an annular portion 111 of the bracket 112 anchored to the base. The annular portion 111 of bracket 112 is provided with a slot 113 in the top thereof and a pin 114, carried by bar 110, is received in slot 113 for effecting sliding movement of bar 110 as pin 114 is reciprocated. This

reciprocation of bar 110 is effected by means of a double-ended lever 115 pivoted at 116 to the upper surface of bracket 113, to be pivotally moved about such pivot 116 in the following manner.

A supporting bracket 117 is anchored to the pillow block 11 in overlying relationship to spindle 6. Such bracket 117 rotatably supports a gear 118 and a heart-shaped cam 119 adapted to be rotated as the gear 118, which meshes the worm 120 provided on spindle 6, is caused to be rotated by such spindle. A plate 121 is held to bracket 117 on the side of such bracket adjacent one end of the double-ended lever 115 and slidably supports a slide bar 122. On the inner face of slide bar 122, pins 123 and 124 project outwardly therefrom to enter into engaging relationship with the surface of cam 119 and effect reciprocation of the slide bar 122 as gear 118 drives cam 119. At one end of the slide bar 122, a tab is turned outwardly therefrom and provides a pin 125 adapted to operatively engage the double-ended lever 115. Thus, it will be observed that as reciprocation of slide bar 122 occurs, lever 115 will effect reciprocation of bar 110 and head 86 therewith. As a result of this arrangement, the head 86, which has wire engaging means, will operate back and forth in a direction parallel to spindle 6 in timed relation with the speed of rotation of the spindle and will thus insure a level winding upon the take-up spool 4.

In rewind such level winding mechanism is not effective because the wire is not in the head. However, the wire being level wound on the take-up spool 4, automatically level winds as it is re-wound on wire spool 3.

When the spools are installed on the apparatus as illustrated in Figures 1, 6 and 7, the forward extremities of spindles 5 and 6 enter into driving engagement with the spools 3 and 4 respectively. To accomplish this, there is provided on the forward end of spindles 5 and 6 annular members 126 and 127 respectively, for effecting this driving engagement with the wire spool and take-up spool.

Inasmuch as each of these annular portions is identical, only one is described. As may be seen in Figure 6, member 127, which engages take-up spool 4, is provided with diametrically opposed keyways, as indicated at 128 and 129, adapted to receive a clip 130. This clip 130, which may be made of spring wire, is bent in the form of a U and provides short inwardly directed leg extremities 131 and 132 substantially normal to the longitudinal axis of such clip. The short legs 131 and 132 are stationed within openings provided therefor in annular member 127, and the bottom of the U frictionally engages the forward face 133 of the keyways formed in such member 127. This clip 130 provides, in two places, a V which is indicated at 134, and each extends outwardly in a direction opposite to the legs formed on such cup.

To provide for mounting spool 4 on spindle 6, such spool has a hub 135 having an axial opening 136 centrally thereof. Opening 136 is sufficient in diameter to receive annular member 127 of spindle 6 and there is provided internally of hub 135 a plurality of longitudinally disposed keyways 137 which are blind at one end. The open ends of such keyways are closed by means of the inner web 138 of spool 4, which is centrally positioned on such spool, and has a central opening 139 of the same diameter as opening 136 in the spool hub. When spool 4 is brought into

position on spindle 6, the circumferential edge of opening 139 in this web 138 engages the slanting side members of clip 130. As the spool is pushed onto the spindle, this engagement causes the web 10 to press each V down, allowing the web to pass over the same. Movement of the spool onto the spindle is then continued until the outer face of web 138 contacts shoulder 140 on member 127. At this time, web 138 has passed over each V on clip 130 and the same spring up into diametrically opposed keyways in the spool hub, securely locking the spool to the spindle.

It will be apparent that, if desired, the member 127 may be omitted and the shaft 6, itself, formed to receive the clip 130. Also, the inward movement of the spool may be limited by engagement of the end of shaft 6 with the end plate of the spool.

It will be observed in Figure 5 that with the 20 spools thus mounted on the spindles, the stretch of wire between the spools is located substantially below capstan roller 56 and head 86. Consequently, it is possible to install the spools without interference between the wire 70 and such 25 members.

As described in the foregoing, the wire is raised from this lowered position by means of pinch roller 60 and glass roller 82 when the control knob is turned to play position. In this manner and 30 without manual aid, it is possible to bring the wire into engagement with capstan roller 56 and into a guide 141 on head 86 which directs the wire into the groove provided therefor in such head.

35 The wire spool and the take-up spool each provides means for automatically stopping the apparatus of the present invention before all wire is removed from either spool. Inasmuch as each is identical, only one is described and Figures 6 and 13 illustrate the same as applied to the take-up spool. As shown, this means consists of a wirelike actuator 142 with a loop 143 therein. Loop 143 is adapted to enter groove 144 provided therefor in spool hub 135. By starting the winding of the wire 70 at a point indicated by arrow 145 in Figure 13, it will be observed that as the wire advances to the right of the hub the same will force loop 143 into groove 144.

As wire is removed from this spool, loop 143 is 50 freed and due to centrifugal force moves outwardly. This allows the straight portion of the actuator, which is slidably positioned within the groove block 146 secured to the outer face of web 138, to move outwardly through an opening 55 in the flange on such web. This outward movement of the actuator continues until arrested by the folded back end of the actuator contacting the lower surface of block 146.

In such outward position, actuator 142 contacts 60 lever 147 fixed to the outer end of shaft 148. Such shaft 148 is journaled for rotation in a bearing provided in the previously mentioned bracket 27. To this shaft 148, the latch plate supporting lever 91 is fixed, and obviously, rotation of shaft 148 will effect shifting of latch plate 87.

70 Normally, lever 147 is in erect position. However, upon being contacted by actuator 142, the same is caused to oscillate. When wire is being unwound from the take-up spool, the same rotates clockwise, and as a result actuator 142 causes lever 147 to move counterclockwise, serving to move lever 91 oppositely for shifting latch plate 87 to the right. Such shifting of latch plate 87 releases pin 97 and permits the control

11

knob to return to off position before all wire is unwound off the spool, as loop 143 is freed before the unwinding wire reaches point 145 on hub 135.

In like manner, the actuator (not shown) provided on the wire spool moves outwardly, upon unwinding of such spool (clockwise), to contact a lever 149. As illustrated in Figure 7, lever 149 is fixed to the outer end of shaft 150 which is rotatably supported by bearing 151 provided by base 1. At the other end of shaft 150, the latch plate supporting lever 90 is fixed, and rotation of shaft 150 will effect shifting of latch plate 87.

Lever 149 is, like lever 147, normally erect. However, upon being contacted by the actuator cammed by wire spool 3, such lever is caused to oscillate. Such oscillation serves to cause shifting of latch plate 87 for releasing pin 97 therefrom and permitting return of the control knob to off position.

The mechanism for applying a retarding force on cup 14 on the spool side of clutch 14-16 which drives spindle 6 and take-up spool 4 and the mechanism for delaying the driving of the capstan roller 56 and thus the feeding of wire until the control means is fully in play position, including the mounting of the capstan roller 56 and capstan drive roller 49 on a pivoted arm as distinguished from a fixed mounting of the rollers, form no part of the present invention but are disclosed and claimed in the copending application of DeVere C. Hollenbeck for Magnetic wire sound recording and reproducing apparatus, Serial No. 681,177, filed concurrently with this application.

It will be clear from the foregoing description that the apparatus shown in the drawings and described above has been illustrated and described in rather specific detail. Obviously, many modifications, changes and departures from the above described construction may be made without departing from the generic spirit and scope of the invention as set forth in the subjoined claims.

What is claimed is:

1. In a magnetic wire sound recording and reproducing mechanism, a wire feeding roller for feeding the wire at substantially uniform rate in one direction, a pivotally mounted pinch roller arm, a pinch roller mounted adjacent the outer end of said arm and adapted to press said wire into engagement with the feeding roller, pinch roller pressure applying means comprising a movable means for exerting constant pressure on the pinch roller arm and adapted to be moved outwardly thereon, and manually operated means for successively swinging the pinch roller arm into operative position and thereafter moving said pinch roller pressure applying means outwardly on said pinch roller arm.

2. In a magnetic wire sound recording and reproducing mechanism, a motor, a motor operated wire feeding roller for feeding the wire at substantially uniform rate in one direction, a pivotally mounted pinch roller arm, a pinch roller mounted adjacent the outer end of said arm and adapted to press said wire into engagement with the feeding roller, pinch roller pressure applying means comprising a spring loaded arm on said pinch roller arm and adapted to be moved outwardly thereon and said spring remain constant length

12

throughout said movement, and control means for successively swinging the pinch roller arm into operative position and thereafter moving said spring loaded arm outwardly on said arm.

3. In a magnetic wire sound recording and reproducing mechanism, a motor, a sound reproducing and recording head, a motor operated wire feeding roll for feeding the wire at substantially uniform rate in one direction, a pivotally mounted pinch roller arm and a second pivotally mounted arm, a pinch roller mounted adjacent the outer end of the pinch roller arm and adapted to press the wire into engagement with the feeding roller, a second roller mounted adjacent the outer end of the secondly mentioned pivotally mounted arm and adapted to bring the wire into said head, pinch roller pressure multiplying means comprising a movable means for exerting constant pressure on the pinch roller arm and adapted to be moved outwardly thereon, and manually operated control means for successively swinging the pinch roller arm into operative position and thereafter moving said pinch roller pressure applying means outwardly on said pinch roller arm and swinging the secondly mentioned arm into operative position.
4. In a magnetic wire sound recording and reproducing mechanism, a base, a motor on said base, a sound reproducing and recording head on said base, means on said base to support wire spools to be selectively driven by said motor, rotatable control means associated therewith to effect winding of the wire from either spool to the other, a motor driven wire feeding roller mounted on said base between said spools for feeding the wire at substantially uniform rate toward one spool, a pinch roller arm and a second arm pivotally mounted on said base and each adapted to be moved into operative position by said control means, a pinch roller mounted adjacent the outer end of the pinch roller arm and adapted to press the wire into engagement with the feeding roller, a second roller mounted adjacent the outer end of the secondly mentioned arm and adapted to bring the wire into said head, pinch roller pressure applying means comprising a member movable along the length of said arm and a spring for causing said member to exert a constant pressure on the pinch roller arm, means actuated by said control means for moving said member outwardly on said arm to increase the pressure exerted by the pinch roller without affecting the effort required to operate said control means.

IRVING A. STONE.
